METHOD AND APPARATUS FOR PROTECT-
ING PUMP BEARINGSJames M. Hait, Los Angeles, Calif., assignor to
Food Machinery Corporation, a corporation of
Delaware

Application March 20, 1936, Serial No. 69,923

6 Claims. (Cl. 103—102)

This invention has to do in a general way with deep well turbine pumps and is more particularly related to the design and operation of the line shaft bearings which are located in the pump assembly or the pumping mechanism below the conventional by-pass port which is generally located in the discharge fitting associated with and mounted on the uppermost bowl in the assembly.

10 As is well known to those familiar with the art, considerable difficulty is experienced in turbine pumps of this character, especially when they are being operated in wells containing sandy water, due to the fact that a pressure differential exists between the ends of the various bearings in the pump assembly and a certain amount of fluid flow consequently takes place through the bearings due to this pressure differential, such fluid flow carrying with it sand particles 20 which eventually cut out the bearings. Various attempts have been made to remove this condition. For example, seals of various kinds have been used with little or no success and under certain circumstances it has been proposed to 25 conduct a clarified high pressure fluid down into the well through auxiliary lines and deliver this fluid into the space between the shaft and the bearing, the pressure of this fluid being maintained at a value sufficient to repel the normal 30 tendency of seepage which arises from the differential pressure between the ends of the bearings referred to above. This procedure is met with difficulty and expense of running a small auxiliary line or a plurality of such lines into the 35 well from the surface of the ground either inside or outside of the pumped fluid delivery tubing. In an effort to overcome this difficulty it has also been proposed to deliver fluid directly from the delivery tubing in the region of the pump 40 assembly into the bearing and to remove the sand and abrasive matter from the fluid delivered in this manner by means of a filter. The use of a filter in this connection, however, meets with two difficulties which render it impractical, if not absolutely inoperative. In the first place, 45 when the pressure fluid is taken from the region of the pump assembly itself and is supplied within the bearings in this same region, the maximum pressure differential which can be obtained 50 under certain circumstances will be so small that the resistance offered by a filter will counteract the differential, making it impossible to supply sufficient fluid pressure within the bearing 55 to repel the normal tendency of fluid flow therethrough. Furthermore, the filter will be-

come clogged with sand and sediment after a very short period in operation which will completely obstruct the flow of fluid therethrough and consequently render the device inoperative.

It therefore becomes a primary object of this 5 invention to provide means for counteracting the normal tendency for fluid flow through the bearings of a deep well turbine pump by applying fluid pressure within the bearing and obtaining such pressure within the region of the pump 10 assembly.

It is a further object of this invention to provide a means of the class described in which the 15 pump bearings are supplied with clarified fluid obtained in the manner above referred to.

It is, as pointed out above, a primary feature of this invention that the fluid which is delivered into the space between the bearing and the shaft is obtained from the pumped fluid delivery tubing and my invention contemplates a 20 novel means and method of obtaining the fluid in this manner in an open conduit arranged and constructed so that the velocity of flow through the conduit is insufficient to support and carry the sand particles contained in the main stream 25 flowing through the delivery conduit. In other words, my invention contemplates the use of a small pressure conduit which has a substantially vertical leg portion opening downwardly into the fluid stream in or immediately adjacent the delivery conduit at a predetermined pressure zone, such pressure conduit having an outlet or discharge opening adjacent the shaft in the region of the bearing. The position of the inlet opening for this pressure conduit is such that the 30 pressure at this point is greater than the pressure normally tending to cause flow through the bearing in question and the system is arranged either through the use of a very small pressure differential between the ends of the bearing in 35 question or through the use of seals associated with the bearing so that the velocity of flow in the pressure conduit is below that which will support and carry sand particles ordinarily suspended in the fluid stream.

45 My invention therefore contemplates the use of an open ended "stilling" or settling chamber positioned with its open bottom end opposed to the direction of flow in the pumped stream so that the sand particles settling from the fluid 50 in this stilling chamber are picked up and carried away by the fluid stream. By arranging the stilling chamber with its opening opposed to the direction of flow, I always obtain the maximum pressure in the region of such opening since such 55

pressure is a composite of the static and kinetic pressures at that point.

Details in the construction and operation of certain preferred forms of my invention will be best understood from the following description of the accompanying drawings which are chosen for illustrative purposes only and in which

Fig. 1 is an elevational view with parts broken away showing the pump assembly and intake manifold of a deep well turbine pump equipped with certain preferred embodiments of my invention.

Fig. 2 is an enlarged sectional elevation taken in a plane represented by the line 2—2 of Fig. 1.

Fig. 3 is a plan section taken in a plane represented by the line 3—3 of Fig. 2.

Fig. 4 is an enlarged plan section taken in a plane represented by the line 4—4 of Fig. 1.

Fig. 5 is an offset sectional elevation taken along the line 5—5 of Fig. 4.

Fig. 6 is an enlarged sectional elevation taken along the line 6—6 of Fig. 1 and illustrating details in the construction of a preferred form of bottom line shaft bearing contemplated by this invention.

Fig. 7 is a fragmentary sectional elevation taken along the line 7—7 of Fig. 3.

Fig. 8 is an enlarged fragmentary sectional elevation taken along the line 8—8 of Fig. 5, and

Fig. 9 is a fragmentary sectional elevation illustrating a modification of the top bearing construction shown in Fig. 5.

More particularly describing the invention as herein illustrated, reference numeral 11 indicates a pump assembly or pumping mechanism which embodies a plurality of bowls indicated generally by reference numerals 11a, 11b and 11c. The uppermost bowl 11a is shown as being formed in combination with a discharge manifold generally indicated by reference numeral 12 which is in threaded engagement with the lower end of a pumped fluid delivery tubing 13. The bottom bowl 11c is shown as being connected with an intake manifold 14 which in turn is connected through the medium of a pipe 15 with a strainer 16.

The bowls 11a etc. are of any conventional construction each being equipped with an impeller 18, such impellers being keyed to a line shaft 19 which extends up through a line shaft enclosing tubing 20 to the surface of the ground where it is supported and driven by any conventional driving means not shown.

It will be understood by those familiar with the art that the number of bowls may be varied, depending upon the depth of the well and the capacity desired in the pumping unit. In the event a plurality of bowls are used, it is generally advisable to separate the bowls at an intermediate point or at intermediate points with what is known as an intermediate shaft bearing fitting, such fitting being indicated in Fig. 1 by reference numeral 23 and being shown as interposed between bowl assemblies 11a and 11b. In addition to having a radial bearing in the fitting 23, the line shaft 19 in this form of my invention also has a radial bearing in the discharge manifold 12 and the lower end of the shaft 19 extends downwardly from the lowermost impeller 18 in the bottom bowl 11c into the intake manifold 14 where it has a radial bearing in the housing generally indicated by reference numeral 25. The housing 25 is supported in the manifold 14 by means of webbing 26 so as to leave a substantially open passage through the periphery

of the housing which forms a part of the pumped fluid delivery conduit.

The intermediate bearing housing 23 as shown in Figs. 2 and 3 is provided with a hub portion 30 supported by webbing members 31 and 32 so as to leave a passage 33 therethrough for the pumped fluid, such hub member containing bearing sleeves 35 which support the section of the line shaft 19 which extends therethrough.

Likewise the discharge member 12 constitutes an open housing which has a hub member 38 extending axially therethrough, such hub member being supported by webs 39 and 39' (see Figs. 4 and 5) and having a bearing sleeve 40 mounted therein in engagement with the shaft 15 19.

As has been previously pointed out, it is a primary object of this invention to provide in a pump assembly of the class described, means for protecting the various bearing members therefrom in from the abrasive action which normally results from the flow of fluid carrying sand particles through the bearings, such flow being set up by the pressure differential between the opposite ends of the bearing. This object is accomplished in a general way by repelling such flow with clear fluid delivered into the region adjacent the shaft in a manner and at a pressure such that the pressure of the clear fluid will oppose the pressure normally tending to cause flow of the sand laden fluid. It was also pointed out that the chief object of this invention was to obtain the pressure fluid so used directly from the pumped stream in a manner such that it was clarified before delivery to the space between the shaft and the bearing.

In Figs. 2 and 3 I show one form of construction which may be employed to effect the foregoing objects in the region of the intermediate bearing 35. In this form of construction the intermediate fitting 23 may be considered as comprising a housing 45 having flanges 46 and 46' at its ends for attachment to the adjacent bowl members. This housing as pointed out above, has an axial hub 30 supported by webbing members 31 and 32 which contains the shaft bearings. In this form of my invention it will be observed that the bearing 35 is formed in segments so as to leave a space 48 at an intermediate point therein, such space being situated opposite a passage 49 extending through the webbing member 32 (see Fig. 7). This passage 49 communicates with a chamber 50 formed on the periphery of the housing 45, such chamber being closed at its upper end and having an opening 51 at its lower end within which a stand pipe 52 is mounted. The lower end of the stand pipe 52 is pressed or otherwise tightly fitted in the opening 51 and is of a length such that its upper open end 53 terminates at or near the top of the chamber 50. The bottom of the pipe 52 is open.

It will be observed that the upper end of the bearing 35 is situated just below the intake or suction portion of the impeller 18 in the bowl assembly above and since the bottom of the hub 30 is situated on the pressure side of the next lower impeller it will be observed that there is a pressure differential between the two ends of the hub 30 which normally tends to cause seepage and flow of pumped sand laden fluid into the hub and through the space between the shaft and the bearing therein. It will be understood of course that the pressure differential between the ends of the bearings at this particular point is comparatively small and it will also be seen

that the pressure at the inlet or mouth of the pipe 52 is greater than the pressure which normally tends to cause flow through the bearing. With this arrangement shown in Figs. 2 and 3, therefore, pressure fluid is delivered into the space between the shaft and the bearing through the port 49 at an intermediate point between the ends of the bearing, the pressure of the fluid so delivered being sufficient to repel the normal tendency to flow. In this arrangement also since the pressure differential is relatively small between the ends of the bearing the velocity at which fluid will be delivered into the space between the shaft and the bearing from the port 49 will be relatively low.

In other words, in the operation of this form of my invention pressure fluid from the pumped stream in the delivery conduit rises through the vertical leg or stand pipe 52 and is delivered into the upper end of the chamber 50 to be subsequently delivered from the port 49 through openings 48 into the space between the shaft and the bearing where it tends to squeeze or seep in both directions and repel any tendency to flow from the ends of the bearing. This fluid is clarified of sand particles since as pointed out above the velocity of flow through the system comprising pipe 52 and the chamber 50 is very small and is consequently insufficient to support and carry sand particles throughout the height of the leg or stand pipe 52. In this way the fluid delivered to the shaft bearing is a clear fluid and since any flow which takes place through the bearing must be comprised of this clear fluid, the cutting action normally encountered is eliminated.

In the form of my invention shown in Figs. 4 and 5, I illustrate one manner in which the same general principles described above may be applied to the bearing in the discharge portion or discharge fitting of the pump assembly. The discharge fitting 12 may also be considered as comprising a substantially open body having a fluid passage 60 extending therethrough between the outer wall of the body and the hub 38.

As is well known to those familiar with the art it is conventional practice to provide the discharge fittings of turbine pumps with by-pass ports which establish connection between the bottom of the shaft enclosing tubing 20 and the water in the well in order to prevent pumped fluid which seeps through the bearings from rising in the enclosing tubing. Such by-pass ports in this form of my invention are shown as being provided in the webbing members 39' and are indicated generally by reference numeral 61 in Figs. 5 and 8. It will be observed that the by-pass conduit 61 communicates with the upper end portion of the hub member 38 in the region at which the bearing member 40 terminates and with this arrangement it will be seen that the pressure differential between the bottom of the bearing 40 and the upper end of such bearing would normally be the difference between the pump pressure at the top of the uppermost stage and the pressure in the well at the region of the outlet fluid by-pass port 61. This last mentioned pressure would either be atmospheric in the event the top bowl assembly was above the water level in the well or at most it would be the static head resulting from the level of water above the by-pass outlet. It will be seen therefore that the greatest tendency for fluid flow and consequently the greatest cutting action resulting from such flow with a sand laden fluid takes place in this bearing.

For the purpose of delivering a clear fluid into the space between the shaft and the bearing at a pressure which will repel such normal tendency to flow, I employ what may be termed a pressure fluid delivery pipe generally indicated by reference numeral 65. This pipe is shown as having a U bend 66 at its upper end so as to provide a substantially vertical leg portion 67 which opens downwardly into the pumped fluid stream so that the pressure applied in the mouth of this vertical leg portion is the composite static and kinetic pressure resulting from the working head of the pump and the velocity of fluid flow in the delivery tubing. The lower end of the pipe 65 is mounted in a chamber 69 formed in the hub 38, such chamber having a duct 70 ported as indicated at 71 so as to discharge through a sleeve member 72 into a space 73 between oppositely disposed seal rings 74 and 75 which engage the shaft and are shown as being positioned below the bearing 40.

The reason for providing the seal rings 74 and 75 is to restrict the passage between the shaft and the bearing so that the velocity of flow between the shaft and bearing and the velocity of flow up through the vertical leg portion 67 is maintained sufficiently low to prevent sand particles being carried upwardly through the full length of this leg. In other words, the passage referred to is restricted and the length of the leg 67 is chosen so that all of the sand normally carried by the fluid stream in the pumped delivery tubing will settle from the fluid in the leg 67 before passing over the U bend 66. The leg 67 like the vertical pipe or leg 52 in Fig. 2 may therefore be considered as a settling chamber, the intake or mouth of which is positioned at a pressure zone in the pumped fluid stream which is greater than the pressure normally tending to cause flow through the bearing adjacent which the conduit system including the leg 67 has its outlet.

In Fig. 6 I show an arrangement operating upon the same general principle discussed above which lends itself particularly to use in connection with the bottom shaft bearing housing 25. The housing 25 is shown as being provided with a seal member 80 at its upper end to restrict the flow of fluid for the same purpose discussed above, the bottom of such housing being provided with a cover cap 81 within which a downwardly extending open ended pipe or leg 82 is secured. This leg 82 has its inlet end positioned in opposed relation to the direction of flow as it enters the intake manifold 14 so that the pressure applied in the mouth of such leg is also a composite static and kinetic pressure which is greater than the pressure at the upper end of the housing which, as will be seen from Fig. 6, is immediately below the intake or suction portion of the impeller 18. The seal 80 retards the flow of fluid between the lower end of the shaft and the bearing 25' and the length of the leg 82 is chosen so that at the velocity encountered the sand particles will not be enabled to rise through this pipe into the space between the shaft and the bearing. It will thus be seen that this arrangement also is effective to deliver a clear pressure fluid into the space between the shaft and the bearing through the medium of a vertical settling tube positioned with its mouth or inlet in the pumped fluid stream.

In the form of my invention shown in Fig. 9 which is a modification of the form shown in Fig. 5, I show the bearing 40' as being cut away

in its outer portion to provide a space 90 extending above and below the discharge 91 from the pressure conduit system which includes a U bent delivery and settling pipe 66'. In this form of 5 my invention I employ sealing members 92 and 92' positioned above and below the ends of the bearing members 40' such bearing having a port 93 situated intermediate its ends, through which the clear pressure fluid is delivered into the space 10 between the bearing and the shaft.

It will be understood that while I have herein described and illustrated certain embodiments of my invention, that the invention is not limited to any of the precise structural details shown and 15 described above, but includes within its scope whatever changes fairly come within the spirit of the appended claims.

I claim as my invention:

1. In combination with the pumping mechanism of a well turbine pump having a line shaft, a line shaft bearing and a pumped fluid delivery conduit: pressure conduit means for delivering fluid from a high pressure region in said delivery conduit into the space between said shaft and said bearing, said last mentioned means including a substantially vertical offset pipe section 20 opening downwardly toward the fluid stream in said delivery conduit and sealing means surrounding said shaft and associated with said pressure conduit whereby the flow of fluid through said bearing is restricted and the flow in 30 said vertical pipe section is thereby maintained of insufficient velocity and turbulence to support sand particles therein.
2. In combination with a turbine well pump of the class described; a housing forming part of the pump assembly and having a passage therethrough forming part of the pumped liquid delivery conduit; a radial bearing in said housing; 40 a line shaft extending through said bearing in engagement therewith; a by-pass conduit formed in said housing with its inner end communicating with the upper end portion of said bearing and its outer end opening into said well; and 45 conduit means for delivering clear high pressure liquid from said pumped liquid delivery conduit into the space between said shaft and said bearing at a point below said by-pass conduit said last mentioned pressure liquid conduit including a substantially vertical offset sand settling tube 50 opening downwardly into the liquid stream in said delivery conduit.
3. In combination with a turbine well pump of the class described; a housing forming part 55 of the pump assembly and having a passage therethrough forming part of the pumped liquid delivery conduit; a radial bearing in said housing; a line shaft extending through said bearing in engagement therewith; a by-pass conduit 60 formed in said housing with its inner end communicating with the upper end portion of said bearing and its outer end opening into said well; conduit means for delivering clear high pressure liquid from said pumped liquid delivery conduit into the space between said shaft and said bearing at a point below said by-pass conduit, said 65 conduit means including a pipe having a substantially vertical inlet portion with an inlet

opening at its lower end opposite the general direction of liquid flow in said delivery conduit; and sealing means surrounding said shaft on opposite sides of the outlet for the pressure liquid conduit and below said shaft bearing.

4. In combination with a turbine well pump: a housing forming part of the pump assembly and having a passage therethrough forming part of the pumped liquid delivery conduit; an axial hub formed in said housing; a bearing member 10 in said hub; a line shaft extending through said bearing in engagement therewith; a by-pass conduit in said housing communicating with the passage through said hub above said bearing and having an outlet opening in said well; conduit 15 means for delivering clear high pressure liquid from said pumped liquid delivery conduit into the space between said shaft and said bearing at an intermediate point on said bearing, said conduit means including a pipe having a substantially vertical inlet portion with an inlet opening at its lower end opposite the general direction of liquid flow in said delivery conduit; and shaft sealing means in said hub between the upper end of said bearing and said by-pass 25 conduit.

5. In combination with a turbine well pump of the class described: a housing forming part of the pump assembly and having a passage therethrough forming part of the pumped liquid 30 delivery conduit; a radial bearing in said housing; a line shaft extending through said bearing in engagement therewith; a by-pass conduit formed in said housing with its inner end communicating with the upper end portion of said 35 bearing and its outer end opening into said well; and conduit means for delivering clear high pressure liquid from said pumped liquid delivery conduit into the space between said shaft and said bearing at a point below said by-pass conduit, 40 said last mentioned pressure liquid conduit including a substantially vertical pipe having a U-bend at its upper end thereby providing a substantially vertical leg having an inlet opening at its lower end opposite the general direction 45 of liquid flow in said delivery tubing.

6. For use in combination with a turbine well pump of the class described having a pumping mechanism, a rotary drive shaft, a bearing associated with said pumping mechanism and engaging said shaft, and housing means forming 50 a liquid delivery conduit, means for delivering liquid free of solid particles to said bearing under a pressure greater than the pressure normally causing liquid flow through the bearing, comprising: conduit means connecting the interior of said bearing and said liquid delivery conduit, said conduit means having a substantially vertical inlet tube offset from said bearing with the inlet opening opposed to the flow of the pumped 55 liquid in said liquid delivering conduit, and means for restricting the flow of liquid through said conduit means whereby any solid particles held in suspension in the pumped liquid are allowed to settle from the fluid entering said tube before 60 the liquid reaches said bearing.

JAMES M. HAIT.
